UNITED STATES PATENT OFFICE.

OLE JACOBSON, OF CHICAGO, ILLINOIS, ASSIGNOR TO THE BANKERS ALARM-PROTECTION COMPANY, OF CHICAGO, ILLINOIS, A CORPORATION OF ILLINOIS.

RELAY FOR BURGLAR-ALARM SYSTEMS.

No. 892,158.

Specification of Letters Patent.

Patented June 30, 1908.

Application filed November 8, 1907. Serial No. 401,250.

To all whom it may concern:

Be it known that I, OLE JACOBSON, a citizen of the United States, residing at Chicago, in the county of Cook and State of Illinois, 5 have invented new and useful Improvements in Relays for Burglar-Alarm Systems, of which the following is a specification.

This invention relates to a relay for a closed circuit local burglar alarm system, and 10 its object is to accomplish with a single instrument all of the results which have heretofore required the use of three separate and independent relays.

More specifically, the invention has for its 15 object to provide a relay of novel construction in a closed circuit burglar alarm system whereby, with the single instrument, the alarm bell may be started ringing and kept ringing until stopped by the closing of the 20 main circuit, all of which is accomplished with a single relay.

In the accompanying drawings illustrating 25 the invention Figure 1 is a plan view of the relay, showing the box in section and the parts in normal positions, the main circuit being closed and the alarm circuit open. Fig. 2 is a detail view. Fig. 3 is a view similar to Fig. 1 showing the alarm circuit closed and maintained by the main circuit. Fig. 4 is a 30 sectional view on the line 4—4 of Fig. 3. Fig. 5 is a view similar to Fig. 1 showing a modified form of my invention. Fig. 6 is a sectional view on the line 6—6 of Fig. 5.

The relay is inclosed within a box 7 having 35 a glass front 8, and it comprises two electromagnets 9, 10 supported on a base plate 11, and an armature 12 also supported on the said base and operating between the electromagnets. The armature is carried by a 40 pivot pin 13 which is pivotally mounted at one end 13' in the base and is held in upright position by an adjusting screw 14 which engages the other end of the pin. The adjusting screw operates through an interiorly 45 threaded sleeve 15 which extends upward through a cross-piece 16 supported on posts 17 mounted on the base. A coil spring 18 has one end fastened to the pivot pin and its other end fastened to a projection 19 on the 50 adjusting disk 20. This disk is held in adjusted position between the collar 15' on sleeve 15 and the cross-piece 16 by frictional engagement therewith. A threaded arm 21 projects from the pivot pin in alinement with 55 the armature and on the opposite side of the

pin and a weight 22 is adjustably mounted on said arm to balance the armature so that the relay may be used in any position. An adjustable contact 23 is mounted in a binding post 24 to be engaged by the armature 60 and this post is insulated from the base and secured to the box. The main circuit is a closed circuit and it comprises a wire 25 leading from the battery B to a binding post 26, a wire 27 to the magnet 9, a wire 28 to binding 65 post 29, a wire 30 to binding post 31, a wire 32 to the magnet 10, a wire 33 to binding post 34 and a wire 35 to the battery. A switch 36 is arranged between wires 30 and 35 so that the electromagnet 10 may be shunted out of 70 the main circuit and enable the return of the armature from the position shown in Fig. 3 to that shown in Fig. 1.

The local alarm circuit comprises a wire 37 leading from the battery B' to binding post 75 38, a wire 39 connected to the base 11, a wire 40 connected to the binding post 24 and the binding post 41, a wire 42 leading from the binding post 41 to the battery and containing a bell 43. In the construction of Figs. 80 1—4 the electromagnets are located between the contact 23 and the pivot of the armature.

The construction shown in Figs. 5 and 6 differs from that shown in Figs. 1—4 in that 85 the electromagnets are located on one side of the pivot of the armature and the contact on the other side. In this construction (Figs. 5 and 6) the arm 21' which carries the balance weight 22' constitutes a part of the armature 90 and engages the contact.

In practice the relay is normally set in the 95 position shown in Fig. 1 in which the armature is attracted to the main relay and switching electromagnet 9 to hold the alarm circuit open. When the main circuit is interfered with by being broken or otherwise the electromagnet 9 will release the armature and the spring will move the armature against the contact 23, thus closing the alarm circuit (Fig. 3) and sounding the alarm. If the 100 interference in the main circuit is then removed the alarm circuit will be held closed by the maintaining electromagnet 10 because the electromagnets are both of the same strength and the electromagnet 10 will, because the 105 armature is adjacent thereto and in co-operation with the spring, hold the armature against the contact 23. To return the armature to its normal position (Fig. 1) the switch 36 may be closed to shunt the electromagnet 110

10 out of circuit and then the electromagnet 9, having greater strength than the spring, will attract the armature.

What I claim and desire to secure by Letters Patent is:

1. A relay for a closed circuit burglar alarm system, comprising a closed main circuit, an electromagnet in said main circuit, an armature normally attracted to said electromagnet, an open alarm circuit, a contact in said alarm circuit, a spring to move the armature against said contact when the main circuit is interfered with to close the alarm circuit, and another electromagnet equal in strength with the first mentioned electromagnet to coöperate with the spring in holding the armature against said contact by the main circuit when the interference in the main circuit is removed.
2. A relay for a closed circuit burglar alarm system, comprising a closed main circuit, a main relay and switching electromagnet in said main circuit, a maintaining electromagnet in said main circuit, an armature between said electromagnets, an open alarm circuit, a contact in said alarm circuit, a spring to move the armature against said contact when the main circuit is interfered with to close the alarm circuit, and a switch in the main circuit to shunt out the maintaining electromagnet when the interference in the main circuit is removed.
3. A relay for a closed circuit burglar alarm system comprising a main circuit, two electromagnets of equal strength in said main

circuit, an armature pivotally mounted to operate between said electromagnets and normally attracted to one of them, an open alarm circuit, a contact in said alarm circuit, and a spring for moving the armature away from the electromagnet to which it is attracted normally and against said contact to close the alarm circuit and in adjacent relation to the other electromagnet when the main circuit is interfered with, said other electromagnet being adapted to hold the armature against the contact and keep the alarm circuit closed if the interference in the main circuit is removed.

4. A relay for a closed circuit burglar alarm system, comprising a metal base, a contact mounted on the base and insulated therefrom, an open alarm circuit including said base and contact, a closed main circuit, a pair of electromagnets in said main circuit, a pivot pin mounted in the base, an armature on said pin and operating between the electromagnets, a spring for moving the armature against the contact when the main circuit is interfered with to close the alarm circuit, an arm on the pivot pin projecting in alignment with the armature and on the opposite side of the pin, a weight adjustably mounted on said arm, and a switch in the main circuit.

OLE JACOBSON.
